UNITED STATES PATENT OFFICE.

GEORGE W. PRENTICE, OF PROVIDENCE, RHODE ISLAND; EMMA FRANCES PRENTICE
EXECUTRIX OF SAID GEORGE W. PRENTICE, DECEASED.

COMBINED BUTTON AND FASTENER.

1,171,640.

Specification of Letters Patent. Patented Feb. 15, 1916.

Application filed August 26, 1912. Serial No. 716,998.

To all whom it may concern:

Be it known that I, GEORGE W. PRENTICE, of the city and county of Providence and State of Rhode Island, have invented certain new and useful Improvements in Combined Buttons and Fasteners; and I do hereby declare the following specification, taken in connection with the accompanying drawings, forming a part of the same, to be a full, clear, and exact description thereof.

The invention relates to a combined button and fastener, that is, to a button which is provided with means for fastening or attaching the same to the fabric to which it is to be applied.

The object of the present invention is to provide a combined button and fastener in which the button-head will be securely held in place upon the fastener and which combined button and fastener is adapted to be applied to the fabric by means of a setting tool without injury to the button-head.

To that end the invention consists in certain features of construction to be herein-after described and claimed.

Referring to the drawings, Figure 1 is a perspective view of a blank for the button-head. Fig. 2 is a view of the fastener to be combined with said button-head blank. Fig. 3 shows the blank in section, with the fastener inserted therein. Fig. 4 is a view of the parts after the button-head has been properly shaped. Fig. 5 is a view of the combined button and fastener as completed by properly bending the legs of the fastener. Fig. 6 shows the legs or prongs of the fastener portion inserted in a piece of fabric. Fig. 7 represents the setting tool in position, the two members of the setting tool being shown in section. Fig. 8 shows the position of the parts after the button has been applied to the fabric by the operation of the setting tool. Fig. 9 is a view of the underside of the fabric having the button attached thereto and showing the position of the legs of the fastener. Fig. 10 is a view corresponding to Fig. 5, but showing the legs of the fastener bent to a somewhat different shape. Fig. 11 is a similar view showing the legs of the fastener bent to a still different shape.

1 represents a blank for the button-head, which may be formed from leather, paper-board, or any other suitable material.

2 represents the fastener which as shown

is formed from a piece of wire bent in the form of a staple and comprising a U portion 3, substantially horizontal portions 4, 4, and legs 5, 5. Preferably the ends of the legs of the staple are beveled, as shown at 5^a, 5^a.

The staple or fastener 2 is inserted in the blank 1 in any suitable manner and by any suitable means. As shown in Fig. 3, the driving of the fastener into the blank serves to embed the U portion of the fastener within the blank, and so that when the button-head 1^a is subsequently shaped and finished the U portion of the fastener will be concealed within the head, as shown in Fig. 4. The projecting legs or prongs 5, 5, are then bent into the form shown in Fig. 5, each leg being so bent as to provide a horizontal portion and with the horizontal portion of one leg lying beside the horizontal portion of the other leg, thereby forming what may be termed a table or abutment 6. As will be seen, the table or bridge-piece 6 lies some distance below the underside of the button-head. The intervening vertical portions of the legs form a shank 7 for the button, and there is also formed a space or opening 8 to receive one member of the setting tool.

As will be seen, the horizontal portions 4, 4, are arranged to immediately underlie the under side of the button-head, and so as to thereby furnish an abutment for the under side of the button-head, and thus prevent any downward movement of the button-head upon the U-shaped portion of the fastener. As the material of the button-head is caused to overlie and is compacted above the upper end of the fastener, the button-head and fastener are, by reason of the presence of the horizontal portions 4, 4, of the fastener, rigidly connected together and securely held in place with relation to each other. The projecting legs or prongs 5, 5, of the combined button and fastener thus formed are then inserted through the fabric 9, as shown in Fig. 6. To attach the combined button and fastener to the fabric the setting tool is applied in the manner indicated in Fig. 7, that is, one member 10 of the setting tool is inserted in the space or opening 8, and so as to act upon the table or abutment 6, while the other member 11 is caused to underlie the free ends of the prongs. The setting tool may be of any 110

suitable construction, as for example, may be of pincers form comprising two members pivoted together. Preferably the member 11 is formed to constitute a die 12 of suitable shape to act upon the free ends of the prongs of the fastener in the manner shown in Fig. 7.

The operation of the setting tool serves to bend the projecting prongs of the fastener into the position shown in Figs. 8 and 9, and to clench the same upon the fabric.

As will be seen, the bending of the prongs of the fastener in the manner shown and described serves to provide a space or opening for the reception of one member of the setting tool, and also to provide a table or abutment for such member of the setting tool to act upon in attaching the combined button and fastener to the fabric. By this construction, therefore, contact of the setting tool with the button-head is entirely avoided, and thus all liability of injury to the button-head in the setting operation is prevented. As will be further seen, the bending of the prongs of the fastener in the manner shown and described also serves to provide a shank for the button, and so that when the combined button and fastener has been attached to the fabric, the under side of the button-head will be located some distance above the fabric, thereby facilitating the application of a button-hook and the manipulation of the same to effect the engagement of the button with the co-operating button-hole.

As will be understood, the prongs of the fastener may be bent in various ways to provide both an abutment for the under side of the button-head and a space for the reception of one member of the setting tool

and a table or abutment for the same to act upon. Thus, as shown in Fig. 10, the horizontal portions 4, 4, of the fastener may be retained and the legs of the fastener immediately below said horizontal portions bent in curved form, and so as to provide a shank 7^a of the form shown in said figure. So also the legs of the fastener may be bent in the form shown in Fig. 11, in which form 50 each leg is bent immediately beneath the button-head into substantially semi-circular form, and so as to form shoulders 4^a, 4^a, and the shank 7^b, as shown in said figure. While this form of shank does not furnish 55 as extensive an abutment for the under side of the button-head, as do the other forms shown, it is sufficient for practical purposes, and this form of shank has the advantage of closely resembling the usual circular 60 shank with which buttons of this character are commonly provided.

What I claim as my invention and desire to secure by Letters Patent is:

1. A combined button and fastener comprising a head and projecting prongs, said prongs being bent to provide an abutment for the under side of the button-head, and an opening adapted to receive one member of a setting tool.

2. A combined button and fastener comprising a head and projecting prongs, said prongs being bent to provide an abutment for the under side of the button-head, and an opening adapted to receive one member of a setting tool, one wall of said opening constituting an abutment adapted to be engaged thereby.

GEORGE W. PRENTICE.
